APPARATUS AND METHOD FOR FITTING STRUTS TO PROPELLER SHAFTS OF BOATS AND THE LIKE

Arthur E. Kammritz, East Hartford, Conn.

Application March 21, 1956, Serial No. 572,960

2 Claims. (Cl. 33—180)

This invention relates to an apparatus for fitting struts to propeller shafts of boats and the like.

In boats having an inboard motor with a propeller shaft extending through the bottom of the boat, the said shaft is generally supported by a single leg strut which includes a bearing surrounding a portion of the shaft, and a leg extending from said bearing and having a foot by means of which the strut is secured to the bottom of the boat. Such single leg struts have been found objectionable for the reason that, due to the single leg, the bearing is supported only in a vertical direction and lateral movement thereof can occur and cause excessive vibration during rotation of the propeller shaft.

Such vibration is practically eliminated by the use of what is known as a V-type strut, i.e., a strut having the bearing and two legs extending upwardly thereon in the shape of a V and each leg having a foot for securing the strut to the bottom of the boat.

Such V-type struts are usually installed on boats to replace the single leg struts and have to be made to conform with the bottom of the boat and with the angle of the propeller shaft relatively to said bottom. This usually involves working with compound angles and it has heretofore been found extremely difficult and inconvenient to fit said struts to the boats because it has been done by the fit and try method which has resulted in considerable loss of time as well as in spoilage of struts on account of errors.

An object of the present invention, therefore, is to provide a novel apparatus which may be adjusted to conform with the exact formation of the boat's bottom and with the disposition of the propeller shaft in relation to said bottom so that said apparatus may then be used for fitting the strut directly thereto in such a manner that, after the strut has been shaped to fit the adjusted apparatus, it will accurately fit on the boat and shaft without any further shaping or fitting.

A further object is to provide a portion of said device in the form hereinafter called a "negative template," which may be adjusted to conform with the boat's bottom and shaft, and another portion in the form hereinafter called the "positive template" that may be adjusted to the conforming negative template and then used in lieu of the actual boat and shaft for accurately fitting the strut thereto before final installation on the boat.

A further object of this invention is to provide an apparatus whereby a negative template may be made directly from the boat wherever it happens to be located, the said negative template then transported to a different location where the strut can be constructed or shaped to accurately conform therewith, and the said strut then delivered to the location of the boat and finally installed without requiring any further fitting.

Further objects and advantages of this invention will be more clearly understood from the following description and the accompanying drawings in which:

2

Fig. 1 is a plan view of the negative template included in my improved apparatus.

Fig. 2 is a rear view thereof.

Fig. 3 is a side view thereof with portions of the boat's bottom and the propeller shaft being indicated in dotted lines.

Fig. 4 is a side view showing the shaft engaging portion of said template in a different position.

Fig. 5 is a front view showing said portion partly in section on line 5—5 of Fig. 4.

Fig. 6 is a side view of an upper portion of said negative template showing one of the members for measuring the angle of the boat's bottom.

Fig. 7 is a side view of the positive template that is included in said apparatus; the position of a strut thereon being indicated in dotted lines.

Fig. 8 is a front view of said positive template and strut.

As shown in the drawings, the negative template of 20 said apparatus includes a pair of crossed supporting bars 5 and 6 on which there are slidably mounted a pair of sleeves 7 and 8, respectively, which are adjustably secured on said bars by clamping screws 9 and 10, respectively. The said sleeves have opposed plate-like 25 projections 11 and 12 thereon which are parallel to and spaced from each other to receive therebetween a stem portion 13 of an elongated V-shaped member 14 which is pivotally mounted between said extensions 11 and 12 by means of a pivot pin 15 and is angularly adjustable 30 on said extensions by a clamping screw 16 which extends through an arcuate slot 17 in said stem portion and is adapted to clamp said stem portion between said projections for securing the member 14 in adjusted positions.

A clamping yoke 18 is pivotally mounted at 19, upon 35 the member 13, by one leg portion thereof and its other leg portion has pivoted thereon a U-shaped loop member 20 which is detachably engageable with a projection 21 on said member 13 for securing the yoke in clamping position. A clamping screw 22 is threaded to and 40 extends through the said yoke for clamping the member 13 to the propeller shaft, as will hereinafter be more fully described.

Adjacent the upper ends of the bars 5 and 6, there 45 are mounted supporting brackets 23 and 23-a which are rigidly secured to their respective bars and have extensions 24 and 24-a from which project studs 25 and 25-a, upon which are rotatably mounted knuckle members 26 and 26-a that are rotatably adjustable on said studs and clamped thereon in adjusted positions 50 by means of clamping screws 27 and 27-a. The said knuckle members have extensions 28 and 28-a with studs 29 and 29-a projecting therefrom on which there are mounted rotatably adjustable measuring plates 30 and 30-a which are adapted to engage the opposite sides 55 of the boat's bottom, indicated at 31, and be adjusted by means of clamping screws 32 and 32-a to conform therewith and thereby provide a measurement of the angular relation between the opposite sides of said bottom and between the said bottom and the propeller shaft when said negative template is mounted upon the propeller shaft indicated at 33, as shown in Fig. 3.

My invention also contemplates the use of a positive template, such as illustrated in Figs. 7 and 8, which 60 preferably includes a base 35 upon which there is horizontally and rigidly mounted a post 36. A supporting bracket 37 is rotatably adjustable upon said post and may be clamped in different positions by means of a clamping screw 38. A pair of angularly disposed supporting bars 39 and 39-a are mounted upon said 65 bracket 37 and carry thereon supporting sleeves 40 and

40-a which are slidably adjustable on said bar by means of clamping screws 41 and 41-a. The said sleeves carry studs 42 and 42-a upon which are rotatably adjustable supporting knuckle members 43 and 43-a which are clamped in adjusted positions by clamping screws 44—44-a and carry studs 45 and 45-a on which are rotatably mounted the plates 46 and 46-a that may be secured in adjusted positions upon said studs by means of clamping screws 47 and 47-a.

The bracket 37 has mounted thereon a horizontally disposed shaft 48 which projects forwardly of said bracket and corresponds to the propeller shaft of the boat and has a standard shank 48-a so that such shafts of different diameters, conforming with the diameters of different propeller shafts, may be mounted upon the bracket 37 and secured thereto by the set screw 37-a. A collar 49 is slidably adjustable on said shaft to provide a stop for locating the strut, as shown in Fig. 7.

As indicated in dotted lines in Figs. 7 and 8, a V-type strut which is to be fitted by means of the above described apparatus consists generally of a tubular portion 50, which provides the bearing for the propeller shaft, a pair of angularly disposed leg portions 51 and 51-a and foot portions 52 and 52-a upon the ends of said leg portions.

In the use of the above described apparatus, the negative template is first adjusted to the exact measurements of the boat which include the angular disposition of the opposite sides of the bottom of the boat with relation to each other, the angular disposition of the propeller shaft 32 with relation to the said bottom and its distance therefrom; said adjustment being made by first clamping the device onto the propeller shaft, in the position illustrated in Fig. 3, so that the rear end 14-a of said member 14 is located upon the point of the shaft where the rear end of the tubular bearing portion of the strut 50 is to be located; this being generally at a point forwardly of the hub of the propeller that is to be mounted on the said shaft.

When the negative template has thus been secured to the propeller shaft, the bars 5 and 6 are adjusted about the pivot point 15 so that they will be substantially vertical and the said bars are then slid in their respective sleeves 7 and 8 and the plates 30 and 30-a are adjusted on said bars into compound angles to bring them into proper contact with the opposite sides of the boat's bottom at the areas that are to be engaged by the foot portions 51 and 51-a of the strut. The said bars and plates are then clamped in adjusted position by means of the clamping screws 9, 10, 16, 27 and 27-a, and 33 and 33-a and the entire negative template is removed from the boat by loosening the clamping screw 22.

The said negative template, having been so adjusted directly upon the boat, may then be transported to another location, which may be distant, where there is suitable equipment for fitting the V-type struts by machining them or forming certain portions thereof to the required dimensions and where there is present the positive template illustrated in Figs. 7 and 8. The positive template is then first adjusted to conform with the adjusted negative template by mounting said negative template upon the shaft 48, with the member 14 clamped onto said shaft so that the rear end 14-a thereof will be located at a suitable locating mark on said shaft, such as the line 53. If desired, this locating mark may be designated by the free end of the said shaft 48.

After the said positive template has thus been secured to the negative template with the rear end of the member 14 in line with the designated locating mark on the shaft 48, the plates 46 and 46-a are adjusted to conform with the disposition of the plates 30 and 30-a of the negative template by adjusting the said template plates to flatly contact the plates 30 and 30-a and then securing them in adjusted positions by tightening the clamping screws 44, 44-a, 47 and 47-a. When the said positive

5 template has been adjusted, as just described above, the stop collar 49 is placed upon the shaft 48 and the tubular portion 50 of the strut is then mounted upon said shaft, as shown in Figs. 7 and 8, and located with its rear end at the locating mark 53. The stop collar 49 is then moved rearwardly against the opposite end of the said tubular portion and secured to the shaft 48 so as to provide a locating stop for the strut. The said strut is then fitted so that the foot portions 52 and 52-a thereof will properly engage the surfaces of the plates 46 and 46-a which correspond to the bottom of the boat. The said strut may be machined while on the template, or removed therefrom and then returned for fitting. The template may also be rotated upon the post 36 to position the strut for machining operations such as drilling or planing.

When the strut has been fitted to the positive template, it is simply removed by pulling it off the shaft 48 and it will then be in shape to accurately fit the boat and may be transported to the location of the boat for final installation.

I claim:

1. An apparatus for fitting a V-type strut to the propeller shaft and bottom of a boat, said apparatus including a negative template having an elongated V-shaped supporting member adapted to be mounted on said propeller shaft and, when so mounted, having its axis parallel to the axis of the shaft, a clamping member for clamping said supporting member to said shaft, the said supporting member having a stem portion, a pair of bar supporting brackets pivotally mounted upon opposite sides of said stem for angular adjustment thereon about an axis transverse to the axis of said supporting member, means for clamping said brackets in adjusted positions on said stem, a pair of supporting bars axially slidable in said brackets with their axes crossing under said supporting member and their upper ends disposed at opposite sides of the supporting member, means for clamping said bars in different axial positions on the brackets, a pair of plate supporting brackets mounted adjacent the upper ends of said bars, a pair of opposed studs projecting from said plate supporting brackets and disposed horizontally on parallel axes transverse to the axis of the supporting member, knuckle members rotatably mounted upon said studs, a pair of plate supporting studs projecting from said knuckle members on axes parallel to the axis of the supporting member, a pair of plate-like members rotatably mounted upon said supporting studs and adjustable upon said bars to compound angles to conform with surfaces of opposite sides of said bottom of the boat, means for securing said plate-like members in adjusted positions upon the knuckle members, and means for securing the knuckle members in adjusted positions upon plate supporting brackets.

2. An apparatus for fitting a strut to a propeller shaft and the opposite sides of the bottom of a boat including a negative template having a supporting member adapted to receive said shaft, clamping means for detachably clamping said supporting member to the shaft, the said supporting member having a stem portion depending therefrom, opposed brackets extending from opposite sides of said stem portion and pivotally mounted thereon for angular adjustment relatively to said supporting member, each of said brackets having an angularly disposed sleeve, a pair of supporting bars slidably mounted in said sleeves with their upper portions in a "V" formation wherein said upper portions are disposed at the opposite sides of the supporting member and project above said member and the axes of said supporting bars intersect under the supporting member, means for clamping the said supporting bars in adjusted positions in the said sleeves, a pair of plate supporting brackets mounted adjacent the upper ends of said supporting bars, a projection on each of said plate supporting brackets, a stud rigidly secured to each of said projections and ex-

tending horizontally therefrom, a knuckle member adjustably mounted upon each of said studs, means for clamping each of said knuckle members to its respective stud in different adjusted positions, a plate-like member rotatably mounted upon each of said knuckle members about an axis extending perpendicular to the axis of the respective stud on the bracket, and means for separately securing each of said plate-like members upon its respective knuckle members in adjusted positions wherein said plate-like members will be disposed in conformity with surfaces of opposite sides of said bottom of the boat.
